CLAIM

The ornamental design for an induction range, as shown and described.

DESCRIPTION

1. Induction range

1.1 is a perspective view of an induction range, showing our new design;

1.2 is a front elevation view thereof;

1.3 is a rear elevation view thereof;

1.4 is a left-side elevation view thereof;

1.5 is a right-side elevation view thereof;

1.6 is a top plan view thereof;

1.7 is a bottom plan view thereof;

1.8 is another perspective view thereof, in a use condition;

1.9 is another front view thereof, in a use condition; and

1.10 is another top plan view thereof, in a use condition.

(Continued)

The broken line showing in the figures is for the purpose of illustrating portions of the induction range and forms no part of the claimed design.

1 Claim, 10 Drawing Sheets
